United States Patent

Des. 237,075
Patented Oct. 7, 1975

237,075

GUN HOLSTER

Robert Taylor, Houston, Tex., assignor to
F-15 Corp., Houston, Tex.

Filed Oct. 24, 1974, Ser. No. 517,501

Term of patent 14 years

Int. Cl. D3—02

U.S. Cl. D22—13

FIG. 2

FIG. 3

FIG. 1

FIG. 4

FIG. 5

FIG. 1 is a front elevational view of a gun holster showing my new design;

FIG. 2 is a top plan view thereof;

FIG. 3 is a left side elevational view thereof;

FIG. 4 is a right side elevational view thereof; and

FIG. 5 is a rear elevational view thereof.

I claim:

The ornamental design for a gun holster, as shown and described.
